PHOSPHINE BORINES AND THEIR
PREPARATION

Ross I. Wagner, Whittier, Calif., assignor to American Potash & Chemical Corporation, a corporation of Delaware

No Drawing. Filed Mar. 14, 1960, Ser. No. 14,553
8 Claims. (Cl. 260—606.5)

This invention relates in general to phosphine borines and more particularly to phosphine borine compounds which are derived from various tertiary phosphines and boron tribromide; these phosphine borines may be added to gasoline which may contain tetraethyl lead (TEL) and which will probably contain ethylene dichloride and dibromide (in the case of automotive fuels) and ethylene dibromide alone (in the case of aviations fuels), the phosphine borines serving to reduce preignition of gasoline used as a motor fuel.

It is the object of this invention to provide for preparation of certain phosphine borines which are particularly useful as preignition additives for gasoline.

Ancillary objects and advantages of this invention, if not specifically set forth, will become apparent in the source of the description which follows.

Broadly, this invention concerns phosphine borines of the general formula $R_3P:BBR_3$, where each R is hydrocarbon and where the number of carbon atoms in the three R groups totals 4 to 30, inclusive.

These materials may be added to unleaded gasoline or gasoline which contains TEL or a similar metal-containing anti-detonant such as methylcyclopentadienyl manganese tricarbonyl, and serve as excellent preignition additives therein, as set forth in greater detail in our co-pending application Serial No. 796,223, filed March 2, 1959.

When the phosphine borines of this invention are added to motor fuel, the resulting motor fuel is found to have a low preignition index and a high resistance to detonation knocking. Another effect of the use of these phosphine borines is to decrease the tendency of the presence of TEL in the gasoline to raise the octane requirement of the engine in which the gasoline is used. A further advantage of these phosphine borines as gasoline additives is that such phosphine borines are highly resistant to hydrolysis, as a result of which they have little tendency to be "leached" from the fuel by the action of such free water as may be present. In this respect, the phosphine borines as a class are decidedly advantageous as compared with most other boron-containing gasoline additives which are highly vulnerable to hydrolysis. The phosphine borines of this invention are also superior to the closely related compounds $R_3P:BCl_3$ and $R_3P:BF_3$ (e.g., $(CH_3)_3P:BCl_3$; $(CH_3)_3P:BF_3$) with respect to hydrolytic stability. For example, in a series of tests wherein 0.81 mg./atoms P/l concentration in leaded gasoline is stored in the presence of water in an iron container for several months (which conditions simulate the environment commonly found in refineries, shipping and storage facilities and in automobile gasoline tanks), it was found that the fluoro derivatives apparently convert to the water soluble dimeric form

2

In similar tests, compounds of the type $R_3P:BCl_3$ were found to be even less satisfactory. On standing, precipitates formed containing boron and nitrogen (from the gasoline). Bromo analogs showed no formation of a precipitate or other deleterious affects of the type encountered with the trifluorides and trichlorides.

A further desirable feature of most of the phosphine bromoborines of this invention is that they are liquids or low-melting solids and all are amply soluble in hydrocarbons. The latter property is especially important in a gasoline additive since additives which have low solubilities have a strong tendency to precipitate and form solid deposits when the fuel mixture is vaporized in the carburetor. It is desirable, but not essential, that the phosphine bromoborines be low-melting materials, since this property also reduces the tendency of the additives to precipitate and form the aforementioned solid deposits. Such deposits cause malfunctioning of the engine in addition to defeating the purpose of feeding the additive into the combustion chamber. Liquids are also desirable from a material-handling standpoint since they may be blended conveniently with liquid fuels.

Also, it is self-evident that if the compounds are to be used as gasoline additives, they must be sufficiently soluble in the hydrocarbon fuel material to provide the desired results. For example, for a standard leaded gasoline containing 3 ml. per gallon of tetraethyl lead, it is necessary that the phosphorus-containing additive be present at 0.3 theory, which represents 3.07 mg.-atoms of P per gallon or 0.81 mg-atoms of P per liter. In the table below, the solubility of certain of the compounds of this invention in petroleum ether is contrasted with the solubility of various other closely related compounds:

35

Compound	M.P., ° C.	Sol. in Unleaded Gasoline-Type Hydrocarbon) B.R. 65-100° C.)	
		g./l.	mmoles/l.
$(CH_3)_2C_2H_4P:BBR_3$	155.5-157.5	1.5	4.4
$CH_3(C_2H_5)P:BBR_3$	120-121	3.2	9.1
$(CH_3)_2P:BBR_3$	207-268	0.175	0.54
$(C_2H_5)_3P:BBR_3$	118-119	5.1	13.8
$(n-C_3H_7)_3P:BBR_3$	159-161	3.05	8.8
$(n-C_4H_9)_3P:BBR_3$	200-201	2.8	6.2

As noted in the table above, the hydrocarbon used was unleaded, but it has been found that the solubility of the phosphine borines in the 65-110° C. B.P. hydrocarbon corresponds closely to the solubility of the same phosphine borines in leaded gasoline. Hence, the table above gives an accurate picture of the solubility of the various phosphine borines in leaded gasoline.

The phosphine borines of the present invention, while sufficiently soluble in hydrocarbons, are relatively insoluble in water and this also tends to maintain quantitative

requirements at low levels since there is essentially no loss by extraction.

Finally, the fact that bromine may here be introduced in the form of the phosphine borine compound permits a reduction in the amount of ethylene dihalide normally required in leaded gasoline; this enables a reduction in costs by providing means for simultaneously controlling ignition and scavenging lead with a single additive.

Such a phosphine bromoborine, when used as a pre-ignition additive for gasoline, combines the known beneficial effects of both boron and phosphorus in a single molecule of relatively small size and lower molecular weight; but, unexpectedly, small amounts of phosphine bromoborines are found to be superior to mixtures of individual commercially-available preignition additives containing phosphorus on the one hand and boron on the other. Further, the phosphine borines are relatively non-reactive and resist decomposition, even at relatively high temperatures.

The range of effective concentrations for these materials and details of their effects on gasoline will not be further described here as this information is set out in the aforementioned co-pending application.

A general preparative method for these new compounds is as follows: To a weighed quantity of the boron tribromide contained in a suitable reaction vessel in added an equimolar quantity of the tertiary phosphine at such a rate that the evolved heat can be dissipated by external means and the reaction mixture may be maintained as a liquid. The reverse addition may be used if more convenient. A large number of tertiary phosphines are known; see, for example, pages 31-37 of Organophosphorus Compounds, Kosolapoff, John Wiley & Sons, New York, 1950.

Specific examples are set forth below showing the preparation of the materials of this invention, but these are for illustrative purposes only and are not to be interpreted as imposing limitations on the scope of the invention other than as set forth in the appended claims.

Example I

Into an evacuated tube cooled to -196°C . were condensed 2.3 g. (25.5 mmoles) dimethylethylphosphine, followed by 6.5 g. (25.9 mmoles) boron tribromide. The tube was sealed and warmed to -78°C . whereupon immediate formation of the adduct dimethylethylphosphine tribromoborine, $(\text{CH}_3)_2\text{C}_2\text{H}_5\text{P:BBR}_3$, occurred. The tube was opened at room temperature and the solid product was recrystallized from ethyl alcohol to give 7.9 g. (23.2 mmoles, 91% yield) of colorless solid melting at 155.5-157.5 $^{\circ}\text{C}$.

Analysis.—Calcd. for $\text{C}_4\text{H}_{11}\text{BBR}_3\text{P}$: P, 9.09; Br, 70.37; B, 3.18. Found: P, 9.01; Br, 70.2; B, 3.15.

Example II

In a similar manner, 1.3 g. (0.0125 mmole) of methyl diethylphosphine and 10.4 g. (41.5 mmoles) of boron tribromide in 30 ml. of hexane yielded 3.4 g. (0.0096 mmole, 77.3% yield) of the adduct methyl diethylphosphine tribromoborine, $\text{CH}_3(\text{C}_2\text{H}_5)_2\text{P:BBR}_3$, from methyl alcohol melting at 120-121 $^{\circ}\text{C}$.

Analysis.—Calcd. for $\text{C}_5\text{H}_{13}\text{BBR}_3\text{P}$: P, 8.73; Br, 67.59; B, 3.05. Found: P, 8.78; Br, 67.50; B, 3.11.

Example III

To a solution of 15 g. (0.127 mole) of triethylphosphine in 150 ml. of hexane cooled to -78°C . by means of a Dry Ice bath was added slowly, with stirring, 37.7 g. (0.15 mole) of boron tribromide under an atmosphere of argon. The resulting white solid was stirred for 15 minutes in the cooling bath and for one hour at room

temperature, after which the solvent and excess boron tribromide were removed by distillation at reduced pressure. The remaining white powder was slurried with 100 ml. of hexane, filtered, washed with hexane, dried and recrystallized from isopropyl alcohol. The yield was 34.6 g. (0.094 mole) 74% of white needles melting at 118-119 $^{\circ}\text{C}$.

Analysis.—Calcd. for $\text{C}_6\text{H}_{15}\text{BBR}_3\text{P}$: P, 8.40; Br, 65.02; B, 2.93. Found: P, 8.45; Br, 64.60; B, 2.92.

Example IV

In a similar manner, 6 g. (0.0375 mole) of tri-n-propylphosphine and 12 g. (0.047 mole) of boron tribromide in 100 ml. of hexane yielded 13 g. (0.032 mole, 84.4%) of white crystals from isopropyl alcohol melting at 159-161 $^{\circ}\text{C}$.

Analysis.—Calcd. for $\text{C}_9\text{H}_{21}\text{BBR}_3\text{P}$: P, 7.54; Br, 58.36; B, 2.63. Found: P, 7.60; Br, 58.58; B, 2.63.

Example V

A nitrogen-swept 250 ml. round-bottom flask was charged with 100.73 g. (0.402 mole) of boron tribromide while the flask was held in an ice bath. To the flask was slowly added 81.33 g. tributylphosphine at such a rate that the reaction mixture was maintained in a fluid state without excessive reflux of the BBR_3 . A good yield of the addition product, $(\text{C}_4\text{H}_9)_3\text{P:BBR}_3$, M.P. 200-201 $^{\circ}\text{C}$., was obtained after recrystallization from either n-propyl alcohol, ethyl acetate, or a methanol-ethyl acetate mixture.

Example VI

In the fashion of Example III above, phenyldimethylphosphine and boron tribromide were reacted both with and without a solvent. The yield was 94%; the compound obtained has a M.P. range of 119-121 $^{\circ}\text{C}$.

Example VII

In a similar manner, the compound

was prepared in a 72% yield and found to have a melting point range of 68-90 $^{\circ}\text{C}$. The wide range was due to the fact that the compound was a mixture of the m- and p-isomers.

Analysis.—Calcd. for $\text{C}_{10}\text{H}_{15}\text{BBR}_3\text{P}$: P, 7.43; Br, 57.52; B, 2.60. Found: P, 7.38; Br, 57.30; B, 2.60.

Example VIII

In a similar manner, compound

was prepared in an 86% yield and found to have a melting point range of 161-163 $^{\circ}\text{C}$.

Analysis.—Calcd. for $\text{C}_{10}\text{H}_{15}\text{BBR}_3\text{P}$: P, 7.43; Br, 57.52; B, 2.60. Found: P, 6.88; Br, 56.86; B, 2.63.

Example IX

In a similar fashion, the compound

was prepared in 88% yield and found to have a melting point range of 107-109 $^{\circ}\text{C}$.

Analysis.—Calcd. for $\text{C}_{16}\text{H}_{27}\text{BBR}_3\text{P}$: P, 6.18; Br, 47.86; B, 2.16. Found: P, 5.99; Br, 47.26; B, 2.21.

Following the method set forth above, various other

materials may be prepared in like fashion; e.g., see the table below.

selected from the class consisting of alkyl and cycloalkyl together with an aryl radical; each of said alkyl radicals

Phosphine	Borine	Phosphine Borine Product
(n-C ₅ H ₁₁) ₃ P	BBr ₃	(n-C ₅ H ₁₁) ₃ P:BBR ₃

As aforementioned, a test for preignition has been devised and the new compounds of this invention have been compared with other closely related compounds, as a result of which the superiority of these compounds has been made apparent. Briefly, this test involves measuring the number of instances per unit time of motor operation in which flames occur in the combustion chamber prior to the time at which the normal flames produced by the spark occur, in general following the procedure described by Hirschler, McCullough and Hall, SAE Trans. 62, 40, (1954). Efficiency of the preignition additive can be measured by the preignition index, which is a percentage of such abnormal flames occurring in the additive-containing test gasoline as compared with the base fuel, i.e., the same TEL-containing gasoline which has not been treated with the preignition additive.

Obviously, many modifications and variations of the invention may be made without departing from the spirit and scope thereof and only such limitations should be imposed as are indicated in the appended claims.

This application is a continuation-in-part of application Serial No. 796,294, filed March 2, 1959, and now abandoned.

I claim:

1. Compounds of the general formula R₃P:BBR₃ where R₃ is selected from the group consisting of two radicals

having between one and twelve carbon atoms, the said R groups together containing from eight to thirty carbon atoms.

2. The compounds of claim 1 wherein at least one R is phenyl.

3. The compounds of claim 1 wherein at least one R is xylyl.

4. The compounds of claim 1 wherein at least one R is ethylphenyl.

5. The compound C₆H₅(CH₃)₂P:BBR₃.

6. The compound C₂H₅C₆H₄(CH₃)₂P:BBR₃.

7. The compounds 2,5-(CH₃)₂C₆H₃(CH₃)₂P:BBR₂.

8. The compound 2,5-(CH₃)₂C₆H₃(n-C₄H₉)₂P:BBR₃.
